UNITED STATES PATENT OFFICE.

MAX CHARLEY WALTER, OF TALMAGE, NEBRASKA.

IRONING-BOARD CABINET.

1,074,226.

Specification of Letters Patent. Patented Sept. 30, 1913.

Application filed October 12, 1912. Serial No. 725,501.

To all whom it may concern:

Be it known that I, MAX C. WALTER, a citizen of the United States, residing at Talmage, in the county of Otoe and State of Nebraska, have invented certain new and useful Improvements in Ironing-Board Cabinets, of which the following is a specification, reference being had to the accompanying drawings.

10 The present invention comprises new and useful improvements in ironing board cabinets.

The primary object of the present invention is to provide means for supporting an ironing board when the same is presented for use and at the same time provide means for the reception of the ironing board when it is not in use thereby being out of the way.

A further object of the present invention 20 is to provide a foldable ironing board which may be readily and easily folded in a compact form and placed out of the way when not in use and which when presented for use will perform the necessary functions of such 25 a device.

With the above and other objects in view the invention consists of the novel details of construction, combination, formation and arrangement of parts as will be hereinafter 30 more fully described, claimed and particularly pointed out in the appended drawings in which—

Figure 1 is a vertical longitudinal section embodying my invention and illustrating the 35 ironing board in an open position, Fig. 2 is a front elevation of the cabinet having the door thereto opened and the ironing board in a folded position, Fig. 3 is a vertical transverse section illustrating the same in a 40 closed position, Fig. 4 is a detail horizontal section on the line 4—4 of Fig. 1, Fig. 5 is a detail view of the bracket, and Fig. 6 is a detail section taken on the line 6—6 of Fig. 5.

45 Reference now being had to the accompanying drawings wherein like and corresponding parts are designated by similar reference characters throughout the several views the numeral 1 indicates an ordinary 50 cabinet of any preferred or well known design having an opening 2 formed in the front wall thereof which is adapted to be closed by a door 3. It is the principal feature of the present invention as set forth 55 in the beginning hereof that this cabinet is

to provide means for supporting an ironing board and also to provide means whereby the ironing board may be folded within the interior of the cabinet and be out of the way. The foldable ironing board which is to be 60 used in conjunction with a cabinet of this character comprises a support 4 bifurcated at its lower extremity to form a pair of standards 5. The lower ends of these standards are provided with hinge members 6 65 which are pivotally connected to a transversely extending bar 7 secured to the floor of the cabinet adjacent the opening 2 formed therein. The upper extremity of this support 4 has hingedly connected thereto as at 70 8 an ironing board 9 of the usual construction. This support 4 obviously provides means for supporting the inner end of the ironing board but to provide means for supporting the opposite end of the ironing 75 board I provide a stay rod 10 which is pivotally connected at one end as at 11 to the floor of the cabinet and its opposite end is slidably connected to the lower face of the ironing board. This slideable connection between the stay rod 10 and the ironing board comprises a plate 12 which depends from the lower face of the ironing board adjacent the free end thereof and has formed therein a longitudinally extending slot 13. The free 80 end of the stay rod 10 is reduced as at 14 and adapted to operate within the said slot 13 and the extremities of the said stay rod are provided with laterally extending lugs 15 which rest upon the upper face of the 85 plate 12 thereby providing a slideable connection between the stay rod and the ironing board which will support the outer end thereof. It is obvious from this construction that when the ironing board is folded 90 within the cabinet the support 4 rests upon the bottom thereof and the ironing board 9 assumes a vertical position within the cabinet and the stay rod 10 will support the ironing board in a vertical position to prevent the same from dropping down. When the ironing board is presented for use it is 95 swung down until it assumes a horizontal position, the standards 5 being brought to vertical position with their lower ends bearing upon the floor of the cabinet thereby supporting one end of the ironing board and when the same has assumed this position the stay rod 10 will support the opposite 100 end of the ironing board. 110

To insure a steady support for the ironing board when the same is presented for use I provide upon the outer face of the support 4 adjacent the upper extremity thereof 5 a pair of laterally extending spring actuated bolts 16. The outer extremities of these bolts are adapted to rest within recesses 17 formed in the front wall of the cabinet and the inner ends of these bolts are provided 10 with offset finger pieces 18 whereby the bolts may be easily removed from the recesses 17 when again folding the ironing board within the cabinet. This ironing board is also provided with a sleeve board 15 19 which may be placed within the interior of the cabinet when not in use and also may rest upon the ironing board when in use.

To provide means for supporting the sleeve board upon the ironing board I provide 20 a base plate 20 which has extending therefrom a standard 21 connected to the sleeve board and the extremities of the plate 20 are bent as at 22 to engage the opposite edges of the ironing board for a purpose 25 which is obvious.

To provide means for supporting the sleeve board when not in use and so the same may be held within the interior of the cabinet I provide upon the inner face of 30 the door 3 a projection 23 so that the lower end of the sleeve board may rest thereupon and the opposite end of the sleeve board is notched as at 24 for the reception of a rotatable latch 25 also carried by the door 3. 35 The inner face of the door is also provided with a shelf 26 which may be used for various purposes.

Hingedly secured as at 27 upon the top of the cabinet is a sectional support 28 40 which comprises a plurality of sections hingedly secured as at 29. Rotatably mounted within the outer extremity of the outer section of the support is an eyelet 30 through which is adapted to extend an electric wire 31 connected at one extremity to a sad iron 32. This eyelet has a slot 30' formed therein which is adapted to register with the opening formed in the outer extremity of the section so that when the slot 50 and opening come in register the electric wire may be inserted therein and the eyelet then rotated thereby providing means for locking the wire within the bracket. This outer extremity is also provided with a 55 groove 33 for supporting the wire of an electric light bulb 34 also in circuit with the line wire 31 as shown. Whereas I have shown electric wires in connection with the support for providing means for supporting the electric light and means for heating the sad iron it is of course to be understood that gas tubes may be substituted

therefor so that a suitable source of light and heat may be supplied as is common.

While in the foregoing I have described 65 and shown the specific embodiment of the present invention it is of course to be understood that other minor details as to changes, formation, alteration and modification may be resorted to that come within 70 the scope of the present invention without departing from the spirit thereof or sacrificing the efficiency of the same.

What I claim:

1. In combination with a cabinet, a support hingedly mounted within said cabinet, an ironing board hingedly mounted at one end upon said support, said support having an opening therein, and means carried by said cabinet and projecting through said opening for supporting the opposite end of said ironing board, substantially as and for the purpose described. 75

2. In a foldable ironing board, the combination with a stationary member, of a support bifurcated at one end to form a pair of standards, said standards being hingedly connected to said stationary member, an ironing board hingedly connected at one end to said support, and a brace rod pivotally 85 connected at one end to said stationary member, said brace rod extending between said standards and being adjustably connected to the opposite end of said ironing board, as and for the purpose described. 90

3. In a foldable ironing board, the combination with a cabinet, of a support hingedly mounted at one end upon the bottom of said cabinet, an ironing board hingedly connected at one end to the opposite end of 100 said support, means carried by said cabinet for supporting the outer end of said ironing board, and means carried by said support and adapted to engage one side of said cabinet to hold said ironing board in 105 open position, as and for the purpose described.

4. In a device of the character described, the combination with a cabinet, of a support hingedly secured at one end thereto, an ironing board hingedly secured at one end to 110 said support, means connected to said cabinet to support the opposite end of said ironing board, and spring pressed bolts mounted upon said support and adapted to engage 11 said cabinet to hold said ironing board in open position, substantially as and for the purpose described.

In testimony whereof I hereunto affix my signature in the presence of two witnesses. 12

MAX CHARLEY WALTER.
